COMBINATION HAND LAMP AND WRITING PAD

Gustaf B. Anderson, Minneapolis, Minn., assignor
of one-half to Oscar T. Nelson, Minneapolis,
Minn.

Application March 12, 1936, Serial No. 68,359

8 Claims. (Cl. 240—6.4)

This invention relates to general utility devices, and the main object is to provide a combination hand lamp, writing pad, and adjustable reflector, all associated in such a manner that the lamp unit may be used as a flash light in the conventional manner, or the reflector may be moved from its normal position over the pad and to an angle and position where it will deflect a part of the light rays passing through the lamp lens toward 10 and over the pad to illuminate the latter and without objectionably interfering with the function of the lamp and lens to illumine objects in advance thereof. A further object is to provide an adjustable reflector that will serve the additional purpose of a pad protector, when the pad is not in use; and which reflector is arcuate in cross section, with dual advantages thereof in that it will better concentrate the reflected light on the writing surface of the pad, when in use, and 15 will more snugly and efficiently embrace or close against the cylindrical lamp unit when not in use. A further object is to provide a simple, efficient, and practical means for compactly securing, supporting, and protecting the writing 20 pad whereby the same will be readily accessible for use, but which will also be neatly enclosed and nested about the lamp unit, when idle, so as not to be objectionably cumbersome or interfere with the normal use, pocketing, or handling of 25 the device. The device is particularly intended for use by meter readers, police, car checkers, time-keepers, reporters, and others who are compelled or find it necessary to write under conditions where there is inadequate light; but of 30 course may be used by anyone having occasion to make notes under such conditions.

In the accompanying drawing, which illustrates a preferred embodiment of the invention:

Fig. 1 is a side elevation of a conventional design of hand lamp or so-called flashlight with my invention incorporated therein, but with the reflector in its closed position.

Fig. 2 is a top or plan view of the left end of the unit, as shown in Fig. 1, but with the reflector and pad holder in their open or operative positions, and with the writing pad removed from the holder.

Fig. 3 is a cross sectional elevation on the line 3—3 in Fig. 2, but with the writing pad in place. Fig. 4 is a side elevation of the head end of the lamp unit showing the reflector and pad attachment in vertical cross section, as on the line 4—4 in Fig. 3.

Fig. 5 is a cross section on the line 5—5 in Fig. 1.

Referring to the drawing more particularly and by reference characters, 6 designates the cylindrical tube or body member of a conventional type of flashlight or hand lamp, having a switch unit 7 for controlling the circuit to the bulb (not shown) which is disposed immediately back of the lens 8 in the head end of the casing. The cylinder or casing 6 is closed at its rear by a threaded cap 9 which is removed when it is desired to insert or substitute dry cells which supply current to the lamp. The lens 8 is held in place by a flanged collar 10 which is threaded on the front end of the casing 6. In the present instance this collar 10 is provided with a rearwardly extending arm 11 which is preferably formed of flat, strap material so as to lie as close as possible against the surface of the casing 6. The pad support consists of a transversely disposed piece of material 12 which when in use is normally disposed in the horizontal position indicated in Figs. 2 and 3. The support 12, however, is formed of springy or resilient material so that it may be bent down into arcuate form over the cylinder 6, as shown in Fig. 5. The support 12 is attached centrally to the strip 11 by spot welding or rivets as indicated at 13 in Fig. 2.

At its front edges the member 12 is provided centrally with a pair of upwardly and inwardly extending tongues 14 under which the writing pad 15 is releasably held as shown.

The reflector 16 is arcuately formed in cross section, and is pivotally secured to the collar or ring 10 as at 17, there being one pivot at each side of the unit. The pivots are also preferably provided with springs 18 which connect the collar 10 with the reflector in such a manner as to yieldably urge the reflector into its upward or open position, as shown in Figs. 2, 3, and 4.

The forward end of the reflector 16 has an inwardly bent flange 19 having an arcuate or curved edge which contacts against the lens 8, as shown in Fig. 4, when the reflector is in open position. This line of contact, however, is sufficiently high so that at least half of the light rays which are normally projected forwardly through the lens 8 will continue to be so directed in order that such light may be employed to illumine objects or numbers in advance of the unit. The light rays above the line of flange contact, however, are directed against the deflector in such a manner and at such an angle that they will be cast over the surface of the pad 15 in order to illuminate such surface when the pad is in use.

To effect additional reflecting action I provide an angular flange 20 at the opposite or normally

rear end of the deflector, and this flange serves the additional purposes of enclosing the rear part of the pad unit, and also eliminates the abruptness of the rear end of the unit so as to facilitate 5 removal of the entire device from a pocket or case in which it may be carried.

A spring held latch 21 is slidably secured to the rear end of the strip 11, and engages an aperture 20^a in the flange 20 to releasably secure the deflector in its closed position. When the latch is 10 manually retracted it releases the flange 20 so that the deflector may move up into its operative position under the combined actions of the springs 18 and the resiliency of the support 12.

15 The use and operation of the device, while no doubt obvious from the foregoing description, may be briefly stated as follows:

Under normal circumstances, and when the 20 pad is not to be used, the flashlight or hand lamp is used in the normal, conventional way and without the giving of any consideration whatever to the writing pad and reflector mechanism. When the operator desires to use the pad he 25 merely releases the latch 21, and if necessary lifts the deflector slightly until it moves to the position shown in Figs. 2, 3, and 4, at which time the deflector flange 19 moves into a position with respect to the lens 8 where it will cut off a part of the light rays and deflect such rays 30 upwardly, rearwardly, and down upon the surface of the writing pad, which pad has assumed the horizontal position indicated in Fig. 3 under the normal, spring action of the support 12.

When the operator has made his notes or 35 memorandums he then closes the deflector back into its initial position, whereupon the holder 12 and pad 15 assume the arcuate position indicated in Fig. 5 until they are again to be called into use. While in this position the pad and holder are 40 entirely enclosed by the deflector, supplemented by flanges 22 at the lateral edges of the member 12. It will be understood that when the pad 15 becomes depleted it can easily be substituted by a new pad or by a fresh supply of cards or sheets 45 if they are employed separately.

It may also be noted that in some instances 50 lamps of this character employ lenses having plane, front surfaces, in which event the forward edge of the flange 19 may be given a corresponding contour or shape in order that it may contact with the surface of the lens in the manner above indicated.

It may also be noted that while it is preferable 55 to attach the pad and reflector unit by means of the ring 10, for which the body 6 is already threaded, the device may be detachably or permanently secured in other ways.

It is understood that suitable modifications 60 may be made in the structure as disclosed, provided such modifications come within the spirit and scope of the appended claims. Having now therefore fully illustrated and described my invention, what I claim to be new and desire to protect by Letters Patent is:

1. The combination with a hand lamp having a cylindrical casing with a lens at one end, of means for supporting a writing pad upon the casing rearwardly of said lens, a reflector pivotally 70 secured to the casing near the lens end thereof and adapted when in operative position to reflect light rays from the lens back and down upon the surface of said pad, said reflector being arcuate in cross section whereby when swung into a rearward position it will cooperate with the casing

to form an arcuate protective enclosure for the pad.

2. The combination with a hand lamp having a cylindrical casing with a lens at one end, of means for supporting a writing pad upon the casing rearwardly of said lens, a reflector pivotally 5 secured to the casing near the lens end thereof and adapted when in operative position to reflect light rays from the lens back and down upon the surface of said pad, said reflector being arcuate 10 in cross section whereby when swung into a rearward position it will cooperate with the casing to form an arcuate protective enclosure for the pad, said pad supporting means comprising a resilient member adapted to be curved downwardly at its 15 sides with the pad to conform with the form of said enclosure.

3. The combination with a hand lamp having a cylindrical casing with a lens at one end, of a horizontal pad support member secured upon the 20 casing and being resilient whereby it may be laterally pressed downwardly to conform with the arcuate surface contour of the casing, and a curved cover hingedly secured to the casing adjacent the support member to form an enclosure 25 over the pad when the latter is not in use, said cover, when in open position, being arranged to deflect light from the lens to the writing surface of the pad.

4. The combination with a hand lamp having 30 a cylindrical casing and a lens at one end thereof, of a pad support mounted on the casing to operatively support a writing pad in horizontal position, said support being transversely yieldable whereby it may be laterally depressed to conform 35 with the curvature of the cylinder, and an adjustable reflector operatively disposed to deflect light from the lens over the writing surface of the pad, said reflector being curved in cross section and adjustable to a position where it will enclose the 40 support and pad when the support is laterally depressed over the casing.

5. The combination with a hand lamp having a cylindrical casing and a lens at one end thereof, of a pad support mounted on the casing to operatively support a writing pad in horizontal position, said support being transversely yieldable whereby it may be laterally depressed to conform 45 with the curvature of the cylinder, and an adjustable reflector operatively disposed to deflect 50 light from the lens over the writing surface of the pad, said reflector being curved in cross section and adjustable to a position where it will enclose the support and pad when the support is laterally depressed over the casing, said reflector 55 having a forward edge movable into contact with the face of the lens at a position where it will intercept part only of the light rays passing therethrough while permitting the balance of the light rays to be employed for illuminating objects 60 or reading matter in front of the lamp.

6. The combination with a hand lamp having a cylindrical casing and a lens at one end thereof, of a pad support mounted on the casing to operatively support a writing pad in horizontal position, said support being transversely yieldable whereby it may be laterally depressed to conform 65 with the curvature of the cylinder, and an adjustable reflector operatively disposed to deflect light from the lens over the writing surface of the pad, said reflector being curved in cross section and having front and rear flanges adapted to enclose the support and pad thereon when in closed position.

7. The combination with a hand lamp having 75

a cylindrical casing and a lens at one end thereof, of a pad support mounted on the casing to operatively support a writing pad in horizontal position, said support being transversely yieldable 5 whereby it may be laterally depressed to conform with the curvature of the cylinder, and an adjustable reflector operatively disposed to deflect light from the lens over the writing surface of the pad, said reflector being curved in cross section 10 and adjustable to a position where it will enclose the support and pad when the support is laterally depressed over the casing, and means for releasably securing the reflector in closed position.

8. The combination with a hand lamp having 15 a cylindrical casing and a lens at one end there-

of, of a pad support mounted on the casing to operatively support a writing pad in horizontal position, said support being transversely yieldable whereby it may be laterally depressed to conform with the curvature of the cylinder, and an adjustable reflector operatively disposed to deflect light from the lens over the writing surface of the pad, said reflector being curved in cross section and adjustable to a position where it will enclose the support and pad when the support is laterally 10 depressed over the casing, and said support having lateral flanges cooperative with the reflector, when closed, to enclose the pad.
